UNITED STATES PATENT OFFICE.

CASSIUS M. WERNER, OF ROCKFORD, ILLINOIS, ASSIGNOR TO HIMSELF AND
EDWIN A. BIGELOW, OF SAME PLACE.

IMPROVEMENT IN HORSESHOES.

Specification forming part of Letters Patent No. 58,355, dated September 25, 1866.

To all whom it may concern:

Be it known that I, CASSIUS M. WERNER, of Rockford, in the county of Winnebago and State of Illinois, have invented a new and useful Improvement in Horseshoes; and I do hereby declare that the following is a full, clear, and exact description of the construction and operation of the same, reference being had to the annexed drawings, making a part of this specification, in which—

Figure 1 is a side elevation of a horseshoe having my improvement attached, and Fig. 2 is a rear view thereof. Fig. 3 is a view, in perspective, of my spring-clamp; and Figs. 4, 5, and 6 are views, in detail, of parts of the same.

It is the object of my invention to securely fasten the horseshoe to the hoof without using nails; and to this end my invention consists in the construction of a band that shall carry projections to be let into the wall of the hoof, and which shall have shoulders at each end, to be fitted into depressions in the rear ends of the shoe, while the front end of the band is held rigidly by a spring-clip fastened above the toe of the shoe.

The shoe A, with its toe B, calks C and C', and rigid clip D above the toe, is made in the usual manner, without being creased or punched for nails.

To the clip D, I rivet a spring-clip, E, on the outside of the shoe, and at a proper distance from the calks I form a slot as broad as the band and as deep as the band is thick, and at the inner edge of this slot, on the under side of the shoe, I sink depressions *a a*. (Shown in dotted lines in Fig. 1.) I now form a band, F, of suitable strength to hold the shoe firmly to the hoof, the ends G and G' of which terminate in a T shape, to match the slot and de-

pressions *a a* in the shoe. The ends of the band are so curved, as at H, Figs. 1, 2, and 3, as that when in place upon the hoof the larger portion of the band will be nearly parallel with the shoe. Inside of the band and at the bends near its ends I secure ribs J centrally, to be let into the wall of the hoof, and they project far enough from the band to give a secure hold when the band is in place. The band is made of a length snugly to fit the hoof, and is held in front by turning down the point of the spring-clip B, as at *b*, over its top in the form of a hook.

Thus prepared, the shoe is fitted to the foot of the horse, and recesses are made in the wall of the hoof to receive the sides of the band with the curved ribs. The ends of the band being inserted in the depressions in the shoe, and the front of the band pressed firmly on the front of the hoof, with the spring-clip turned down upon it, will hold the shoe securely in place, while the turning up of the hook of the spring-clip will permit the front of the band to be raised and the shoe removed.

What I claim as my invention, and desire to secure by Letters Patent, is—

1. The combination of the band F with the shoe A, constructed, arranged, and operating substantially in the manner described, for the purpose set forth.
2. The combination of the ribs J with the band F, arranged and operating substantially in the manner and for the purpose set forth.

In testimony whereof I have hereunto subscribed my name.

C. M. WERNER.
